COMBINED ADDING MACHINE AND PENCIL BOX

Jack Fairchild Fleming, Summit, N. J., assignor to Sterling
Plastics Company, Union, N. J., a corporation of New
Jersey

Application February 5, 1954, Serial No. 28,883

Term of patent 14 years

(Cl. D74—21)

Fig. 1 is a top plan view of a combined adding machine and pencil box showing my new design, as it appears in partially opened position;

Fig. 2 is a side elevational view thereof as it appears in closed position; and

Fig. 3 is an end elevational view thereof.

The drawing is stippled to indicate contrasting portions.
I claim:

The ornamental design for a combined adding machine and pencil box, substantially as shown and described.
